UNITED STATES PATENT OFFICE.

J. NOTTINGHAM SMITH, OF JERSEY CITY, NEW JERSEY, ASSIGNOR TO HIMSELF AND W. B. HEADLEY, OF SAME PLACE.

IMPROVEMENT IN EXPLOSIVE PROJECTILES.

Specification forming part of Letters Patent No. 40,888, dated December 3, 1863; antedated December 1, 1863.

To all whom it may concern:

Be it known that I, JOSEPH NOTTINGHAM SMITH, of Jersey City, in the county of Hudson and State of New Jersey, have invented a new and Improved Explosive Projectile; and I do hereby declare that the following is a full and exact description thereof, reference being had to the accompanying drawings, making part of this specification—

Figure 1 being an outside view of the projectile; Fig. 2, a central longitudinal section thereof; Fig. 3, a transverse section, near the rear end.

Like letters designate corresponding parts in all the figures.

The missile consists of two principal parts—the shaft A, together with the charge of powder, and the head B. The rear end, C, of the shaft A is also a shell of itself. The shaft A fills the whole length of the bore of the mortar or ordnance from which it is thrown, while the head B remains outside of the muzzle. There are two principal advantages gained by this arrangement: First, it obviates the resistance of the atmospheric pressure against the projectile in the gun; second, it enables the head B to be larger than the bore of the gun, and of any desired shape, so that advantage is taken of this to add spiral or oblique wings M M to its periphery, substantially as represented, to give a revolving motion to the projectile, constantly increasing in velocity as it passes through the air. This construction also enables me to use a peculiar protecting-cap, G, the office and advantages of which will presently appear. The head B is divided into an even number (generally four) of separate chambers or cavities b b, which, when cast without the central bolt, E, of the shaft, are all in one chamber, and readily molded with cores; but when the head is placed on the shaft A, over its central bolt, E, the cavities are thereby divided into separate ones, but communicating by single small apertures s s, Fig. 2, so that they may explode simultaneously. Within each of these cavities b b is located a hammer or elbow-shaped lever, H. It has a rounded pivot hub or ball, located in a suitable socket in the wall of the head, wherein it is allowed a vibratory movement to the ex-

tent required. The inner arm, h, of each hammer projects transversely into the cavity of the head, while the outer arm, f, projects outward and forward through and somewhat beyond the outer surface of the shell, substantially as shown in Fig. 2.

Upon the inner arm, h, of the alternate or opposite hammers are respectively situated nipples e e, for percussion-caps or their equivalents, so that when the outer projecting arms, f f, of the hammers are suddenly forced backward, and the inner arms, by consequence, driven forward, the percussion-caps strike suitable hammer-faces on the interior surface of the shell-case, as indicated at y, Fig. 2, and are exploded thereby, thus igniting the explosive material in the head B. The intermediate alternate or opposite hammer-arms, h h, are connected with wires l l, which extend back through the central hollow of the shaft A, for the purpose of actuating hammers m m in the rear end of the projectile, to explode percussion-caps n n, and thereby simultaneously ignite the explosive material in both the front and rear ends of the missile. The cap G is secured upon the projecting end of the shaft-bolt E by nut and screw K, and it has as many arms g g as there are hammers H H. The arms g g are placed in front of the spiral wings M M, and serve to direct the air thereto, and assist in their action. In the rear end of each of these arms is a cavity, u, which fits over, without touching, one of the projecting arms f of its hammer, and thus secures it from premature explosion by any accidental shock produced in handling or firing off. Each arm g also fits closely and tightly over said hammer-arm, being suitably packed for the purpose, thereby protecting the explosive material from dampness and exposure; but while these cap-arms thus serve as protectors to the exploding-hammers, in the act of handling and firing, on the other hand, when the projectile reaches its destination, they promote the sure explosion of the shell. To this end the arms g g are made quite small and weak at one place, w, in each, so that they are readily broken there when an object is struck, and the consequent forcing backward of the broken arms adds greatly to the certainty of acting on the

hammers, and thereby exploding the shell. The hammers *m m* in the rear end of the missile are located in a hammer-chamber, *N N*, and vents communicate, through the nipples *n n* forward, to the explosive material of the shaft *A*. Thus the hammers are free to move, unimpeded by the explosive material itself. The wires *l l* and the forward motion of the missile keep the hammers back from prematurely exploding the caps. A central aperture, *r*, in this hammer-case affords a communication from the front cavity, *a*, of the shaft backward to additional shell *C D* in the extreme rear end of the projectile. The shell *C* is divided into several distinct chambers, *c c*, Fig. 3, separated by partitions, but all communicating with the central aperture when cast, so as to be molded with cores in one piece. This central cavity is filled by the plug *D*, thus completely separating the chambers *c c* into close apartments, except small notches *q q*, through which lugs or projections *p p* of the plug *D* pass, and then, by turning part way round against inclined surfaces, the plug is tightly held in place. These notches *q q* finally serve as fuse-openings to the chambers *c c*. There is also a fuse-plug, *r*, similarly secured for the inner end of the shell-plug *D*. The plug *D* is packed at *v*, as shown, as well as the plug *r*. In the periphery of the shaft *A* are also cavities *i i*, all communicating with the central fuse-chamber, *a*, and in each of these cavities is a small shell, *I*, with fuse-plug *j*, to be fired from the common fuse-chamber *a*. All of these little shells explode after the projectile strikes, and they are driven from

it in all directions. These cavities *i i* are arranged in longitudinal rows, as shown, so that the weakest parts of the shaft are in those longitudinal lines, in order that the shaft may divide in those lines, and have its fragments sent in all directions.

What I claim as my invention, and desire to secure by Letters Patent, is—

1. The arrangement of the bent levers *H H* in pivot-sockets in the wall of the missile, as also in relation to the front and rear shells, so as to simultaneously fulfill the two functions of direct hammers, and, through connecting wires, of operating other hammers in a distinct part of the missile, substantially as herein specified.
2. The protecting-cap *G*, with its hollow cap-arms *g g*, constructed, arranged, and operating substantially as herein set forth.
3. The arrangement of the spiral wings *M M*, in combination with the arms *g g* of the cap *G*, as herein set forth.
4. Locating separate shells in the extreme ends of the projectile, and exploding them simultaneously by the connecting-wires *l l*, or their equivalent, substantially as herein described.
5. The separate inclosed hammer-chambers *N N*, as set forth.
6. The peculiar construction and combination of the rear multi-chambered shell *C* and plug *D*, as set forth.

J. NOTTINGHAM SMITH.
